UNITED STATES PATENT OFFICE.

WEBSTER W. TEAGUE, OF MARION, INDIANA.

CONTAINER.

Application filed March 25, 1925. Serial No. 18,281.

This invention relates to containers, and contemplates the provision of a comparatively light sanitary and air proof construction, possessing great temperature resisting qualities which makes it particularly useful for packing and shipping perishable products, the container being simple, strong and durable in construction.

In the drawing forming part of this application, like numerals of reference indicate similar parts in the several views, and wherein:

Figure 1 is a perspective view.

Figure 2 is a sectional view on line 2—2 of Figure 1.

Figure 3 is a sectional view on line 3—3 of Figure 1.

Figure 4 is a fragmentary view of the reinforcing annulus.

Figure 5 is a fragmentary view of the metallic portion of the top of the container.

Before entering into a detail description of what is herein shown, I desire to have it understood that while the container may be constructed from any suitable material, it is preferably made from fibrous material suitably reinforced to provide a more substantial and convenient construction, and that the container can be manufactured in any desired size and cross sectional contour without departing from the spirit of the invention.

The container herein illustrated comprising a body portion 10, a bottom 11 and a cover 12. The bottom 11 is inserted from the lower edge of the body portion 10 as clearly illustrated in Figure 2, and is formed with a depending flange 13, the inner periphery of which is tapered toward its lower edge. The flange 13 is adapted to engage the adjacent surface of the body portion 10 when the bottom is placed in position, the bottom being braced and effectively held secured to the body 10 by a reinforcing member consisting of an annulus of substantially U-shaped formation in cross section, the inner and outer sides of which are indicated at 14 and 15 respectively. The annulus is thus designed to embrace the lower edge of the body portion 10 by the flange 13 in the manner illustrated in Figure 2, the inner side of the said annulus being offset inwardly to provide a flange 16 upon which the

bottom 11 reposes. This edge of course is split along spaced parallel lines 17 to allow it to be arranged in the manner shown in Figure 2, while it will be noted upon inspection of this figure that the outer side 15 of the annulus projects an appreciable distance above the bottom 11 and is formed at 60 suitably spaced points with indentations 18 adapted to bite into the adjacent portion of the body 10.

The top 12 is constructed from the same material as the body and bottom 11, and may be of any desired thickness, the top including a depending flange 19 of metal or other suitable material, the upper edge of which is offset inwardly as at 20 and arranged between two thicknesses of material 70 constituting the top. The flange 19 is split along spaced parallel lines 21 to allow the upper edge thereof to be offset inwardly as described, and each portion 22 defined by splitting the material as stated is formed 75 with an opening 23 adapted to receive a suitable adhesive substance to assist in holding the flange 19 associated with the top 12. It is manifest that both the top and bottom of the container are afforded maximum 80 strength and rigidity without materially increasing the weight of the container as a whole, and that the structure may be rendered water tight, as well as air proof. It is also simple in construction and can be 85 manufactured and sold at a nominal cost.

While it is believed that from the foregoing description, the nature and advantages of the invention will be readily apparent, I desire to have it understood that I 90 do not limit myself to what is herein shown and described, and that such changes may be resorted to when desired as fall within the scope of what is claimed.

Having thus described the invention, I 95 claim:

A container including a cylindrical body portion, a cover therefor, a bottom inset from the lower edge of the body portion and including a depending annular tapering 100 flange terminating flush with the lower edge of the body portion and having its inner face tapered toward its free edge, an annular reinforcing member of substantially U-shaped formation in cross section de- 105 signed to embrace the lower edge of the

body portion and said flange and shaped to conform to the tapering of said flange, the outer side of said reinforcing member projecting an appreciable distance above said bottom, projections carried thereby and designed to bight into said body portion, the inner walls of said reinforcing member terminating to provide an inwardly directed flange, said flange being provided with a plurality of slits along spaced parallel lines 10 to impart resiliency to said flange, and said flange abutting the lower face of the bottom for supporting said bottom in position.

In testimony whereof I affix my signature.

WEBSTER W. TEAGUE.
